UNITED STATES PATENT OFFICE.

FREDERICK WILLSON AND HARRY F. SHINDEL, OF READING, PENNSYLVANIA,
ASSIGNORS TO WILLSON GOGGLES INC., OF READING, PENNSYLVANIA, A CORPOR-
ATION OF PENNSYLVANIA.

EYE-PROTECTOR ATTACHMENT FOR SPECTACLES.

Application filed July 1, 1922. Serial No. 572,132.

To all whom it may concern:

Be it known that we, FREDERICK WILLSON and HARRY F. SHINDEL, both citizens of the United States, residing at Reading, in the 5 county of Berks and State of Pennsylvania, have invented certain new and useful Improvements in Eye-Protector Attachments for Spectacles, of which the following is a specification.

10 This invention relates particularly to attachments for spectacles or eye-glasses which provide removably secured protection glasses in front of the correction glasses as shown in Patent No. 1,433,690, of Oct. 31, 1922; and it consists in the improvements 15 fully set forth in connection with the accompanying drawings and clearly defined in the subjoined claims.

Fig. 1 is a rear-view elevation of a protection-glass eye-cup embodying our present invention, shown attached to an eye-glass rim; Fig. 2 being a similar view showing a modified device applied to a templed spectacle rim, with a side shield extension of the 25 cup indicated.

Fig. 3 is an enlarged cross-sectional view of the eye-cup attachment, on the line 3—3 of Fig. 1; and Fig. 4 is an enlarged end view of the same.

30 As shown in Figs. 1, 3, and 4 our complete device consists of a protection glass eye cup 10, formed of a split-ring band of sheet material which provides an enclosing wall for the inserted rimmed eye glass 3 as in the 35 patent previously referred to; said wall band however being adapted to clamp or release the protection glass 13, and being also provided with improved clips for engaging the inserted correction-glass rim, as herein- 40 after described. In Fig. 2, which shows the device in connection with a templed spectacle rim, a separately formed hinged side shield is indicated adapting the same for use as complete goggles, and the preferred clamping means for the protection-glass is omitted and a modified arrangement 45 of the rim-engaging clips indicated.

The adjacent free ends 11—11 of the split wall band 10, are bent over outwardly to 50 form clamping eyes and in these eyes is engaged a tapered staple connection 12 adapted, by upward and downward movement respectively, to either clamp the rim-edge 14

of the band upon the protection glass 13 or to release the latter, as desired; the inwardly turned ends of this clamping device being adapted also, as shown, to form a head-band connection for conveniently securing the eye cup device and the engaged eye-glass frame to the head of the wearer.

55 The attaching devices for the correction-glass frame, upon the inner wall of the eye cup, comprise a fixed device 20—21—22 adapted to provide pivotal engagement for the rim-and-nose piece junction 7 of the former as in our prior application referred to. In our present construction, the spring clip devices provided for engaging the outer portion 60 of the correction glass rim, are formed by separate spring-metal strips 15, 15, secured to the inner wall of the eye cup band with their free rim-engaging ends 16, 16, arranged to swing in a plane substantially parallel to the plane of the clamped protection glass; so that said clip ends, after being 65 first engaged with the outer portion of a correction glass rim, and then swung outward to permit engagement of the latter with the fixed device 20—21—22, will lie in the plane 70 of the secured correction glass rim. The 75 extensions 17, 17 of the attached ends of these clip strips 15, 15, are shown as bent inwardly to form yielding abutments when the eye cup band 10 is clamped upon the protection glass 13 by clamping device 12.

80 This advantageous clamping arrangement for the protection glass may be omitted when the eye cup device is applied to a spectacle frame having a head connecting temple piece as indicated in Fig. 2; and the 85 arrangement of the spring-clip strips 15, 15 may obviously be modified as indicated in 90 said Fig. 2.

95 What we claim is:

An eye-protector attachment for spectacles consisting of a protection-glass eye-cup having a rim-enclosing wall provided 95 interiorly with a spring clip having its free end adapted to swing in a plane approximately parallel with the plane of the protection-glass and to engage an inserted spectacle rim.

100 In testimony whereof we affix our signatures.

FREDERICK WILLSON.
HARRY F. SHINDEL.
